UNITED STATES PATENT OFFICE.

JACOB WILLIAM LATTIG, OF WYNCOTE, AND CHARLES LANE GOODRUM, OF PHILADELPHIA, PENNSYLVANIA, ASSIGNORS TO EASTERN TELEPHONE MANUFACTURING COMPANY, OF WEST CHESTER, PENNSYLVANIA, A CORPORATION OF PENNSYLVANIA.

TELEPHONE TRUNKING SYSTEM.

No. 829,164.

Specification of Letters Patent.

Patented Aug. 21, 1906.

Application filed October 22, 1903. Serial No. 178,110.

29 all whom it may concern:

Be it known that we, JACOB WILLIAM LATTIG, residing at Wyncote, Montgomery county, and CHARLES LANE GOODRUM, residing at Philadelphia, county of Philadelphia, Pennsylvania, citizens of the United States, have invented a certain new and useful Improvement in Telephone Trunking Systems, of which the following is a specification.

10 Our invention relates to telephone-exchange systems, and more particularly to such systems as employ a common battery or batteries located at each central office for the purpose of signaling to and from the exchange. It has for its object the provision of 15 means whereby the trunk connections between different portions of the same exchange or between different exchanges may be more perfectly controlled and the work 20 more easily and certainly accomplished than heretofore.

In all exchange-work efficiency of operation is the end constantly sought. Assuming that metallic circuits are employed with 25 standard apparatus, so that satisfactory talking conditions are assured, improvements in efficiency must contemplate the connection and disconnection of subscribers either in the same time with less labor or in less 30 time with the same labor, or both in less time and with less labor. Since the general adoption of common batteries supplying energy from the central offices for all purposes, it has been found possible to employ automatic signals which by their display or concealment 35 inform the operators accurately not only of the condition of the circuits with which they are working, but as to the acts of the subscribers they are connecting and of other operators who may be assisting in making the 40 connections. In our previous patent, No. 722,367, dated March 10, 1903, and reissued September 8, 1903, as No. 12,156, we have described and claimed a common-battery 45 system employing such automatic signals for the subscribers' lines and in connection with the cord-circuits. The cord-circuit or supervisory signals are depended upon by a subscriber's operator to indicate the condition of 50 the subscribers' lines during connection. When a call has been made, the supervisory signal corresponding to the calling-plug indi-

cates when the called subscriber answers. In transferring a connection through a trunk-line to another operator whether in the same 55 or a distant exchange, however, it has not been found practicable heretofore to depend entirely upon the supervisory signals at the answering or initiating switchboard-section. In many cases systems have been installed 60 wherein the responsibility is divided between the subscribers or "A" operator and the trunk or "B" operator, the former initiating the trunk connection and the latter then assuming supervision and control over the 65 same. Such a practice is not productive of the highest efficiency, inasmuch as the "A" operator's work lacks uniformity and the failure of instant co-operation between the operators may result in delays or in the calling-line being temporarily "hung up." In 70 order to prevent such miscarriages, which are especially liable to occur where the traffic is heavy, elaborate arrangements of trunk-signaling have been devised which are not only 75 cumbersome in themselves but by introducing new combinations only increase the complexity of the operations they are meant to simplify.

According to our present invention we impose upon the "A" operator the entire responsibility for every connection, so arranging the trunk connections that her ordinary supervisory signals may be depended upon for all necessary information whether in a 85 simple connection or in trunking, and by the provision of simple means we enable the "A" operator to control, as well as supervise, the "B" operator's work. To this end and without being necessarily restricted to our system 90 above mentioned we arrange the supervisory signals at the "A" operator's station, so that in trunking they can be affected by the main battery at the "B" operator's station, the current-flow therefrom being determined by 95 the insertion of the trunk-plug at the "B" end and by the called subscriber, and we arrange a signal in the trunk at the "B" end adapted to take current from the main battery at that end, the flow of said current being determined by the insertion in or withdrawal from the trunk-jack of the "A" operator's calling-plug. By this arrangement 100 the "A" operator's work is rendered uniform,

as she not only supervises all connections, but also rings up the called subscriber in every case and effects the disconnection in every case in response to the usual signals.

5 Our invention is susceptible of application to any system employing a bridged battery, and by installing such a battery it may be applied even to magneto systems. As a matter of convenience we have shown and shall 10 describe it in connection with the circuits of our aforesaid patent; but it is understood that we are not limited thereto.

Our invention is illustrated in the accompanying drawing, wherein the figure is a diagram showing two switchboards A and B, with the operator's apparatus and an interconnecting trunk-line.

Referring to the drawing, X is a subscriber's telephone-station connected to the 20 central station A by line-wires 1 and 2. At station X are provided the usual pieces of apparatus, comprising the transmitter T, the receiver T', the polarized bell Q, the condenser C, and the switch-hook H. The line-wires 1 and 2 pass to the central office and there by means of extensions 3 and 4 are connected to the terminal bus-bars 5 and 6 of the main battery A'. Interposed between the line and the bus-bars are the impedance- 25 coils I and I', which serve to limit the current-flow in the line and also to prevent the passage of voice-waves over the bus-bars 5 and 6. Connected in the No. 1 side of line is the relay R, whose armature r controls the 30 circuit 19 of the line signal-lamp L. Connected to line outside of this relay are the multiple jacks J, each having a pair of springs j j' and a sleeve-contact or thimble j''. Each spring j is connected to the No. 1 side of line, and each spring j' is connected to the extension 3 between the relay R and the impedance-coil I. Each thimble j'' is connected to the No. 2 side of line. When a plug is inserted in any of these jacks, the relay 40 R is short-circuited at the springs j j' by the tip of the plug.

The organization of circuits and apparatus at subscriber's station Y and thence to the central office B is the same as that just described. The line-jacks at office B are lettered J³, and the main battery is B'.

It will be understood that in the diagram we have shown a single subscriber's station X and its line leading to the central office, 55 with the terminal apparatus; but this is supposed to be multiplied as many times as there are subscribers connected to that exchange. We have shown jacks J³, representing the terminals of an additional subscriber's line, which is supposed to be connected in similar manner to the line 1 2. In order to connect these lines for conversation, the subscriber's operator is provided with the usual complement of cords, plugs, and auxiliary apparatus, one set of which is illus-

trated. Plugs P and P' are united by the cord conductors 8 10 and 9 11, each side of the cord being inductively continuous for alternating currents, but conductively discontinuous for direct currents by reason of the inclusion of condensers C' and C².

The main battery A', in addition to its terminal bus-bars 5 and 6, is provided with an intermediate bus-bar 7, connected at such a point as to render the differences of potential unequal, or, in other words, the battery is organized in two divisions or sections a and a', as fully described in our patent hereinbefore referred to. Connected by conductors 12 and 13 between the cord conductor 9 and the bus-bar 7 is the polarized supervisory relay R', and similarly connected by wires 12 and 14 between the bus-bar 7 and the cord conductor 11 is the polarized supervisory relay R². The armature r' of relay R' is normally drawn to the right by a retractile spring aided by the permanent magnetism, and when moved to the left against the tension of the spring it closes the circuit 15 17 of the supervisory lamp L'. The armature r² of the relay R² in a similar manner controls the circuit 16 17 of the supervisory lamp L². In connection with the cord-circuit the key K serves to connect the operator's telephone O for testing and listening in the usual manner, 95 while the key K' is the ordinary ringing-key, which breaks the cord conductors 10 11 and connects the calling-generator to the plug P'.

The ordinary operation of the system thus far described is fully set forth in our patent above referred to and therefore it need not be given here in detail. Briefly outlined, it is as follows: Subscriber X calls by taking down his receiver, whereupon the current-flow in his line from the battery A' energizes the relay R and lights the lamp L. The insertion of answering-plug P short-circuits the relay and puts out the lamp, at the same time connecting the supervisory relay R' in the following circuit: battery-section a', bus-bar 7, wire 12, relay R', wires 13 and 9, sleeve of plug and thimble j'' of the jack, wire 4, bus-bar 5, and back to the battery. As the subscriber's circuit is closed a branch is also closed from the thimble j'' by way of line-wire 2 to the subscriber's station, back by line-wire 1 to the bus-bar 6 and battery-section a. The difference of potential between the bus-bar 7 and the jack-thimble j'' will be the algebraic sum of the potential differences due to the sections a and a' acting against each other, and the resultant current-flow through the relay-windings will keep the armature r' in its normal or inoperative position. Supposing the desired connection to be with the jack J³, key K is closed and the tip of plug P' is applied to the thimble of jack J³ to make the busy test. If the line is idle, the tip and the jack-thimble j'' will be at the same potential; but if the line is busy the

jack-thimble will be connected back through another cord conductor 11 to the bus-bar 7, and a click will be heard in the receiver. In testing the tip of the plug is connected 5 through the key K and the operator's set by wire 18 and through coil I² to the bus-wire 5, to which the sleeve j² of each jack is also connected through wire 4 and coil I'. When a line is busy, all the test-thimbles j² of that 10 line are connected through the plug that is in through its cord conductor 9 or 11 through the corresponding supervisory relay and wire 12 to bus-wire 7. Such a connection therefore raises the potential of the test-thimbles j² with respect to the plug-tip by just the difference between bus-wires 5 and 15 7 due to the battery-section a'. Assuming the former to be the case, the plug P' is fully inserted in the jack, thereby closing the circuit 20, 14; 11, j², 20, 25, and 5 of the relay R², which thereupon lights the lamp L². The ringing-key K' is then used to call the subscriber and upon his answering the lamp L² goes out, as in the case of the calling subscriber. 25

In case the wanted line is connected to another exchange or to another switchboard in the same exchange it will be necessary to trunk the connection. Suppose, for example, subscriber Y, connected to exchange B, is wanted. For the purpose of such connections trunk-lines are provided typified by a single circuit in the diagram. Trunk-line 20 30 21 extends from central station A to central station B, terminating at the former in the trunk-jack J' and at the latter in the plug P². The thimble j² of the jack J' is connected through conductor 20 to the sleeve of the plug P², and the spring j³ of the jack is connected by conductor 21 to the tip of the plug. When not in use, the spring j³ rests upon an anvil j⁴ to short-circuit or cross the two sides of the trunk-line together. 40

At station B we interpose in the trunk-conductor 21 a relay R³, whose armature r³ controls the local circuit 23 of the trunk signal-lamp L³, supplied by a battery B³, which may be common to a considerable number of circuits, as indicated by the short branch lines shown. In order that the relay-winding 45 may not impede the transmission of speech-waves or of the alternating ringing-current, we preferably provide a shunt 22, containing a suitable condenser C³.

Accompanying each group of trunk-lines between the stations A and B we provide an operator's instruction-circuit 24, connected to the "B" operator's telephone O' and adapted to be connected to the "A" operator's telephone O in any suitable manner, as 55 by the key K².

The operation of the complete system thus described where a connection is to be trunked is as follows: Suppose subscriber X to have 60 called and that he has been answered by the

"A" operator, as already described. Suppose subscriber Y to be wanted. The "A" operator connects herself with the "B" operator and repeats the number wanted. The "B" operator answers by designating the trunk to be used. Assuming this to be the trunk 20 21, the "A" operator inserts the plug P' in jack J', thereby separating spring j³ from the anvil j⁴ and connecting cord conductors 10 11 to the trunk-conductors 21 and 20, respectively. This produces no effect on the supervisory relay R². The "B" operator then takes up the plug P² and inserts it in a jack J² of subscriber Y's line. It should be observed that the intermediate bus-bar 7 at each central station is grounded. Hence the insertion of the plug P² immediately completes a circuit for the supervisory relay R² at station A, as follows: Battery-section b', bus-bar 7 (at station B,) through the ground to bus-bar 7 at station A, by wire 12 to relay R², wire 14, cord conductor 11, jack-thimble j², conductor 20, the sleeve of plug P², the thimble of jack J², and thence by wire 25 to the bus-bar 5. The relay R² thereupon throws over its armature r² and lights the lamp L², indicating to the "A" operator that the plug P² has been inserted in the wanted line-jack. It will be observed that this operation is exactly the same as if the "A" operator had inserted her calling-plug P' directly into the wanted jack. The "A" operator then proceeds to ring up by means of the key K', precisely the same as in any other case. When subscriber Y answers by taking down his receiver, the difference of potential existing between his jack-thimble and the intermediate bus-bar 7 is reversed, because he thereby closes the following circuit: from the jack-thimble by line-wire 2 to substation Y, back by line-wire 1 to the central office and through wire 26 to the bus-bar 6. The relay R² being connected through conductor 20 on one side and the ground on the other with the jack-thimble j² and the bus-bar 7, respectively, the reversal of potential and the consequent reversal in current-flow cause the relay to throw back its armature into inoperative position, extinguishing the lamp L². This indicates to the "A" operator that the call has been answered. In this also it will be observed the operation is precisely the same as in making a direct connection without trunking. When the conversation has been terminated and subscribers X and Y have restored their receivers to the hooks, thereby breaking their circuits, both supervisory lamps L¹ and L² immediately light. Relay R' is energized at this juncture by current from the battery-section a', while the relay R² receives its current from the battery-section b' at station B. "A" operator then clears out by removing all plugs from the jacks. The first result of this is to break the circuits of the relays R' and R², so that their armatures again assume the 125 130

position shown, and the lamps L' and L^2 become dark, so to remain until their cord-circuit is again brought into requisition. The second result is the crossing of the trunk-conductors 20 21 in the jack J' by the closure of the spring j^3 upon its anvil j^4 . The plug P^2 being still in the jack J^2 a circuit is thus created for the relay R^3 , as follows: battery B' , bus-bar 5, wire 25, sleeve j^2 , plug P^2 , conductor 20, anvil j^4 , spring j^3 , conductor 21, relay R^3 , tip of plug P^2 , jack-spring and wire 26 to bus-bar 6, and back to the battery. Current in this circuit immediately energizes the relay R^3 , whose armature r^3 closes the circuit 23 and lights the lamp L^3 . This indicates to the "B" operator that the trunk-line is idle and should be disconnected.

It will be found that this arrangement of circuits and signals provides for every contingency that may arise in ordinary practice without in the least complicating the work of either "A" or "B" operators, but rather simplifying the same over the arrangements now in use. Suppose, for example, that the "A" operator has received the trunk-number and has inserted the plug P' , but the "B" operator has neglected to complete the connection. Supervisory lamp L^2 remains dark, and as the "A" operator has not yet rung the subscriber this gives her an infallible indication, whereupon she may again resort to her instruction-circuit 24. This contingency may occur through the "B" operator misunderstanding or not catching the number, in which case she has only to wait without making the connection, being assured that the "A" operator will come back on the instruction-circuit when she perceives the connection is incomplete. Again, in making a connection if the "A" operator should misunderstand the trunk-number, and therefore fail to insert the plug P^2 in the trunk-jack, the trunk operator would immediately be advised of the fact as soon as she inserted the plug P^2 in the wanted line-jack by the lighting of her lamp L^3 . In such case the number would be repeated over the instruction-circuit.

Having thus described our invention, what we claim, and desire to secure by Letters Patent, is—

1. In a telephone-exchange system, two switchboard sections or stations each comprising the following instrumentalities: subscribers' line-terminals, plugs and cord-circuits for interconnecting the same, supervisory-signal devices connected to the cord-circuits, a source of current and connections whereby the supervisory-signal devices may be operated thereby; together with a trunk-circuit interconnecting the switchboard sections or stations, and means whereby in making a connection through said trunk from one station to the other, the supervisory signals of the cord-circuit at one station will be op-

erated by the current from the source at the other station, substantially as described.

2. In a telephone-exchange system, two central stations, a common battery at each station having end terminals and a grounded intermediate terminal, subscribers' lines fed from said batteries, a trunk-line interconnecting the stations and a cord-circuit at one station for interconnecting the lines thereat with each other or with the trunk-line, means at the other station to interconnect the trunk-line with the subscribers' lines thereat so arranged as to connect the component line-wires at the two central stations in the same order as when interconnected directly at either station, a supervisory-signal device connected between the intermediate battery-terminal and one side of the cord-circuit at the first station, and means at the subscribers' stations to maintain their line-circuits closed during the use of their apparatus, whereby the supervisory-signal device will become energized by current from one side or division of one or the other main battery when a direct connection is made or when a trunk connection is completed, and will be deenergized when the called subscriber answers, in either case, substantially as described.

3. In a telephone-exchange system, two central stations, a common battery at each station, subscribers' lines fed from said batteries, a trunk-line interconnecting the stations and a cord-circuit for interconnecting the lines thereat with each other or with the trunk-line, means at the other station to interconnect the trunk-line with the subscribers' lines thereat, a supervisory-signal device connected with the cord-circuit at the first station, and means whereby in a direct cord connection between subscribers in the same exchange the supervisory-signal device will derive current from the main battery at said first station, but in making trunk connections the said signal device will derive current from the battery at the other station, substantially as described.

4. In a telephone-exchange system two central stations, a trunk-line extending between them together with subscribers' line-terminals adapted to be connected through the trunk, a circuit-closer at the first station normally maintaining the two sides of the trunk directly closed together, a signal device included in the trunk at the second station, a battery at the second station, and means becoming operative upon completing connection with a subscriber's line to bring said battery into connection with the trunk, substantially as described.

5. In a telephone-exchange system, two switchboard stations or sections with subscribers' lines terminating at each and a trunk-line extending between the sections, a signal-circuit formed in part of the trunk-line, a cir-

cuit-closer at the first section normally maintaining said signal-circuit in signaling condition but operable to change said condition when a line is connected to the trunk, a signal device at the second section in said circuit, a source of current-supply also at the said second section or station, and means to connect the same to the signal-circuit when the trunk-line is connected finally to the subscriber's line, substantially as described.

6. In a telephone-exchange system two switchboard stations or sections, subscribers' lines on each, a trunk-line between the stations, a circuit-closer at one station for the trunk actuated in making connection therewith, a signal device connected to the trunk

at the other station, a battery also at the other station, and means to connect said battery to the trunk in connecting the latter with the subscriber's line, whereby the signal is 20 normally inactive, but during connection is under the control of the initiating or subscriber's operator, substantially as described.

In testimony whereof we have hereunto set our hands, in the presence of two subscribing witnesses, this 19th day of October, A. D. 1903.

JACOB WILLIAM LATTIG.
CHARLES LANE GOODRUM.
